UNITED STATES PATENT OFFICE.

ALFRED J. GAIRING, OF JOHNSTOWN, PENNSYLVANIA, ASSIGNOR TO THE LORAIN STEEL COMPANY, OF PENNSYLVANIA.

LOCKING DEVICE FOR ARMATURE OIL-GUARDS.

SPECIFICATION forming part of Letters Patent No. 654,391, dated July 24, 1900.

Application filed December 28, 1899. Serial No. 741,812. (No model.)

To all whom it may concern:

Be it known that I, ALFRED J. GAIRING, of Johnstown, in the county of Cambria and State of Pennsylvania, have invented a new 5 and useful Improvement in Locking Devices for Armature Oil-Guards, of which the following is a full, clear, and exact description, reference being had to the accompanying drawings, which form a part of this specification.

10 My invention has relation to a locking device for the oil-guards of electric motors and dynamos and for other purposes, and is particularly designed for use in motors and dynamos wherein the oil-guards are in the form of 15 separate removable sleeve members which are secured around the armature-shaft intermediate the shaft-bearings and the armature-heads and are overhung by the commutator or by the end extension of the armature-20 winding. Inasmuch as these overhanging parts, particularly in small machines, are of small internal diameter the guards are not accessible to the application of ordinary locking devices, and considerable trouble has been 25 experienced in shop practice in properly securing them in place. It is a matter of considerable importance that they be securely fastened, since if they become loose and work endwise toward the shaft-bearings they may 30 lock the armature between the said bearings and result in its destruction. On the other hand, they must be capable of being readily removed when desired to permit access to 35 other parts of the armature and its commutator.

The present invention is designed to provide means of simple and efficient character for securing the above-stated results and which may also be used to advantage in other classes 40 of machines where it becomes necessary to secure one small part to another at a point which is difficult of access.

With this object in view the invention consists in the novel device and in the novel construction and combination of parts, all as 45 hereinafter described, and pointed out in the appended claims, reference being had to the accompanying drawings, in which—

Figure 1 is a view, partly in side elevation 50 and partly in longitudinal vertical section, of

the commutator end portion of an electric motor of the railway type having my invention applied thereto; and Fig. 2 is a detail view of the locking device detached. Fig. 3 is a detail view showing the device seated. 55

In the drawings, the letter A designates the armature-shaft; B, the armature-body having the head B'; C, the commutator; C', the commutator-clamp; D, the motor-frame, and E the shaft-bearing. These parts may be 60 constructed in any usual or well-known manner, as my invention does not relate thereto.

G designates the oil-guard, which consists of a sleeve having a flared or bell-shaped guard end. This sleeve in the present instance is 65 threaded onto the extended hub portion B² of the head B' and against the end of the commutator-clamp C', which it locks in place. At the other end of the motor the corresponding guard is usually driven to its seat on the 70 hub of the other head. This, however, is not material to my invention.

The purpose of these guards, as is well known, is to prevent lubricant from the oil-wells or lubricant-reservoirs in which the 75 guard ends are seated from working back onto the armature.

H designates my improved locking device, which consists of an oblique steel pin having at its upper end an extended arm or head H', 80 provided with a perforation h near its end, said pin and arm forming an obtuse angle with each other. To receive this pin, a hole is drilled obliquely through the guard-sleeve G in the hub B², and the pin is inserted 85 therein to its full length, which can be readily done notwithstanding the overhanging end portion of the commutator. To seat the arm H', whose outer end preferably extends to a point somewhat beyond the end of the commutator, the sleeve may be slightly planed out to form a recess. The sleeve portion of the guard G is also formed with a through-perforation which registers with the perforation in the arm H', and after the pin has been 95 properly seated a small rivet I, of copper or some other soft material, is passed up through the registering perforations from within the sleeve and its upper end subsequently upset. When for any reason it is desired to remove 100

the oil-guard, the head of this rivet can be readily cut off and the pin removed.

It is obvious that the shape of the pin and the arrangement of the parts may be varied 5 in detail without departing from my invention. Hence I do not wish to be limited to the exact construction and arrangement which I have herein shown and described.

The motor shown is an ordinary railway-10 motor having its frame D constructed in two sections, the line of division being at right angles to the plane of the section shown in Fig. 1 and hidden by the armature.

Having thus described my invention, what 15 I claim, and desire to protect by Letters Patent, is—

1. The herein-described locking device, consisting of an oblique pin having an extended arm forming a head therefor, and a 20 perforation in said arm, substantially as described.

2. The combination of a sleeve member, and a member upon which said sleeve member is seated, said sleeve member having an 25 oblique hole extending through it into its seating member, and a pin seated in said hole and having an extended arm which seats on

said sleeve member and is secured thereto, substantially as described.

3. The combination of a sleeve member and 30 a member upon which the sleeve member is seated, said sleeve member having an oblique hole extending through it into the seating member, a pin seated in said hole and having an extended arm or head which seats on the 35 sleeve member, and means for securing said arm or head to the said sleeve member, substantially as described.

4. In a dynamo-electric machine, the combination with the armature having an over-hanging portion, of an oil-guard extending underneath said overhanging portion, a pin 40 extending obliquely through said guard into the armature member upon which the guard is seated, said pin having a head portion 45 which extends beyond the said overhanging portion and which is secured to said sleeve, substantially as described.

In testimony whereof I have affixed my signature in presence of two witnesses.

ALFRED J. GAIRING.
